CONTAINER

Alden James Schneider, Greenwich, Conn., and William Edward Taylor, Fairfield, and George Ernest Eckman, Oradell, N.J., assignors to American Can Company, New York, N.Y., a corporation of New Jersey

Filed Dec. 20, 1962, Ser. No. 246,029

4 Claims. (Cl. 220—53)

The present invention relates to containers, and has particular reference to a hermetically sealed sheet metal reclosure can which may be opened by the simple process of peeling from its body a circumferentially extending pull tape to uncover a circumferential slit which partly separates the upper portion of the can from its bottom portion, and then bending the upper portion upwardly to break the body along a score line to complete its separation.

In recent years, great emphasis has been given to the development of consumer packages which have added appeal to the consumer because of special consumer convenience features which they offer. One of the most highly prized of such features is ease of opening. However, although it is comparatively simple to embody easy opening features in containers made of soft, easily tearable materials such as paper and plastic, it is much more difficult in the case of the sturdier sheet metal cans which are closed by means of tamperproof, double seamed end members, and such cans have thus heretofore usually required the use of an opening tool such as an opening key or a can opener to effect the opening operation.

The present invention solves this problem by providing a hermetically sealed can wherein the can body is provided with a precut circumferential slit which extends around the major portion of the can body just below its upper end seam and is sealed by an external sealing tape which can be easily stripped from the body to uncover the slit and permit ready detachment of the upper portion of the can.

To reinforce the slit area of the body against inadvertent breakthrough or displacement of the abutting slit edges, a suitable internal reinforcement in the form of a separate or integral collar is disposed inwardly of the slit. In addition to its reinforcing function, the collar provides a seat for the detached upper portion of the can so that it can be used as a reclosure after the initial opening of the can.

In order to permit economical manufacture of the instant can, the slit is not extended completely around the body, but is terminated short of each side of the side seam area so that the body blank remains at all times during its manufacture a unitary, self-sustaining member which can be handled by the high speed automatic equipment on which cans must be made in order to be economically competitive with other types of containers. The unslit portion of the body between the ends of the slit is, however, scored so that when the tape is removed and the upper portion of the body hinged upwardly around the scored body portion by the ultimate consumer, the flexing of the scored metal causes the body to break along the score line, thus completing the severance of the upper can portion and permitting it to be completely removed from the lower portion of the can to provide a convenient reclosure.

An object of the invention, therefore, is the provision of an easily opened, hermetically sealed reclosure can.

Another object of the invention is the provision of an

2

easily opened can which can be made on high speed, automatic equipment.

Yet another object is the provision of a can which may be easily opened merely by the removal therefrom of an easily peelable sealing tape and a subsequent upward hinging of the body along a short breakable hinge section.

Numerous other objects and advantages of the invention will be apparent as it is better understood from the following description, which, taken in connection with the accompanying drawings, discloses a preferred embodiment thereof.

Referring to the drawings:

FIGURE 1 is an elevational view of a can embodying the concepts of the instant invention;

15 FIG. 2 is an enlarged fragmentary view of an upper portion of the can of FIG. 1, the view showing the side seam area of the can with the sealing tape partially peeled from the can body to initiate the can opening operation;

FIG. 3 is a plan view of the exterior surface of a flat 20 blank for making the body of the can shown in FIG. 1;

FIG. 4 is a vertical section, on an enlarged scale, taken substantially along the line 4—4 in FIG. 2;

FIG. 5 is a sectional view taken substantially along the line 5—5 in FIG. 1;

25 FIG. 6 is a sectional view taken substantially along the line 6—6 in FIG. 3; and

FIG. 7 is a view similar to FIG. 4 but illustrating a modified form of the invention.

As a preferred and exemplary embodiment of the instant invention, the drawings illustrate a sheet metal can which is formed with a tubular, preferably cylindrical body 10 which is formed from a flat, single-piece, sheet metal blank 12 (see FIG. 3) which has its opposite side edge portions 14, 16 suitably notched and slit to form 30 hook portions 18, 20 so that when the blank is bent to tubular form to form the body 10, the edge portions 14, 16 may be joined in a soldered side seam 22 wherein the upper and lower portions 24, 26 comprise lap sections and the intermediate portion 28 comprises a lock section 35 40 wherein the hooks 18, 20 are reversely folded and interlocked with each other (see FIG. 1).

The opposite ends of the body 10 are sealed by imperforate top and bottom end members 30, 32, respectively, which are secured thereto in hermetic, compound lined double seams 34.

45 The body 10 closely below the top double seam 34 is completely cut through to provide a circumferential slit 36 which extends around the major portion of the body and terminates just short of both sides of the upper lap 50 portion 24 of the soldered side seam 22, as best seen in FIGS. 1 and 2. Between the separated ends of the slit 36, the sheet metal of the body 10, including both layers of the lap seam portion 24, is partially cut through to provide a score line 38 which connects the ends of the slit 36.

55 The slit 36 is covered over and sealed against leakage by a thin, narrow tape 40 which is bonded to the outside surface of the can body 10 and extends circumferentially around the can and also terminates short of either side 60 of the side seam 22, so that it does not interfere with the side seam forming operations.

The tape 40 preferably comprises an external layer of aluminum foil 42 and a layer of a thermoplastic resin 44 which is heat sealed to the can body 10 to create a hermetic, liquid proof seal around the slit 36.

65 One end of the tape 40 is not bonded to the body 10, but is doubled back on itself to form a pull tab 46, the

resin layers in the pull tab being heat sealed together to form a sturdier structure which affords a better grip for the consumer (see FIG. 5).

One type of thermoplastic resin which has been found to be suitable for use as the resin 44 is a random copolymer of ethylene and acrylic acid having a copolymerized acrylic acid content in the neighborhood of 3% (plus or minus 0.5%) by weight, based on copolymer weight, and a melt index of 8, plus or minus 1.

When measured at 23° C., this material has the following approximate physical properties:

Density	.923.
Tensile strength	1720 p.s.i.
Tensile impact	1500 p.s.i.
Yield strength	1345 p.s.i.
Elongation	520%
Rigidity	1.5×10^4 p.s.i.
Hardness (Shore C)	80.

Peel tests with this ethylene-acrylic acid copolymer wherein two strips of tin plate, each $\frac{3}{4}$ " wide, which are adhered to each other by an interposed layer of this copolymer are pulled apart at an 180° angle at a speed of 1 inch per minute and a temperature of 77° F. indicate a peel strength of about 2.4 lbs. per $\frac{3}{4}$ lineal inch.

This ethylene-acrylic acid copolymer preferably is extruded directly onto the aluminum foil layer 42 while in a molten state. The most practical way of accomplishing this is to extrude the resin onto a large web of aluminum foil and to then cut the tape 40 from the resultant foil-resin lamination. It has been found that a tape 40 of sufficient strength and flexibility to meet the normal requirements of the instant container is produced when the foil layer 42 is about 0.003 inch thick and the resin layer 44 is about 1 mil thick. These thicknesses can of course be varied to meet specific can requirements.

The tape 40 is preferably applied to the body blank 12 while the latter is in the flat, as seen in FIG. 3, so that it forms a patch over the slit 36 which has the effect of reinforcing the slit blank and thus permitting it to be handled by automatic can making equipment in much the same manner as is an unslit blank. This application of the tape may be easily effected by heating the body blank 12 to a temperature of about 325° F. to 345° F. and pressing the tape against the blank under moderate pressure. It is desirable to avoid overheating the blank, lest this result in degradation of the resin 44. If this occurs, the tape will not peel cleanly but will leave a residue on the blank.

It will be understood that although the above described ethylene-acrylic acid copolymer is well suited for use as the thermoplastic resin 44 of the instant container, it is by no means the only material suitable for this purpose; and other compositions having generally comparable sealing and peeling characteristics may be substituted.

In order to support the can body 10 inwardly of the slit 36 and thus prevent inadvertent relative displacement between the can body portions above and below the slit during shipment and storage of the filled, sealed can and during the can manufacturing operations wherein endwise compressive forces are exerted on the body, such as the die flanging operation and the end seaming operations, the body 10 is provided with an interior collar which engages tightly within the body inwardly of the slit 36. The collar may either be a separate collar 50 (see FIG. 4) which is formed with an upper, inwardly curled edge 52 and has its bottom edge portion 54 expanded outwardly into a groove 56 formed in the body 10 to securely lock the collar in place, or an integral folded collar 58 which is created by a double reverse folding of the body 10 in the slit area so that two layers of the body 10 lie inwardly of the slit 36 to form the collar 58. Reference is had to United States Letters Patent 1,615,930 issued to W. E. Burns on February 1, 1927 on

Can and Method of Forming for further details regarding this folded wall construction.

In addition to its reinforcing function, the collar provides a reclosure seat for the can reclosure which is created in the can opening operation, as will now be described.

When the consumer desires to open the sealed can, he grasps the free pull tab 46 and pulls radially outwardly on it, thus peeling the tape 40 from the can body 10 until it is completely detached. The upper portion of the can which is disposed above the slit 36 is then moved upwardly in a hinging action in which the score line 38 serves as the fulcrum. The resultant bending or flexing of the scored metal of the score line 38 results in the breaking of the body along the score line 38 thereby completing the severance of the upper portion of the can from the lower portion and permitting its complete detachment therefrom for use as a separate reclosure which, when repositioned in frictional engagement with the collar 50, protects the unused portion of the contents of the can.

The instant can is particularly suitable for use as a coffee can, since it is capable of holding the high vacuum under which coffee is initially packed, as well as the low to moderate gas pressures which are eventually evolved by the ground coffee. It has been determined that most users of ground coffee expect to hear a sudden outrush of the coffee-generated gas as soon as the initial hermetic seal on the can is broken. In the present can, it has been found that the heated resin 44 frequently flows to a greater or lesser extent into the slit 36 during the heat sealing operation and thereby seals it so that this gas cannot escape from the can until the upper portion of the can is hinged upwardly. This latter hinging action permits so much of the gas to escape that the characteristic hissing sound which results from the escape of trapped gas through a comparatively small opening is absent, thereby leading some consumers to mistakenly assume that the can has not been hermetically sealed.

In order to prevent this, a small perforated opening or orifice 60 is provided in the can body 10 at the juncture of the slit 36 and score line 38 on the pull tab side of the side seam 22. Thus, when the pull tab 46 of the tape is grasped and pulled to strip the tape 38 from the body 12, the opening 60 is uncovered almost immediately and the gas in the can escapes with the characteristic hissing sound which is so reassuring to the consumer. This occurs because of the fact that the collar does not lie in sufficiently tight or intimate contact with the outwardly disposed body portion to create a hermetic sealing relationship therebetween, and consequently the gas is enabled to flow in the minute space between the collar and the can body and reach the opening 60 in sufficient quantity to create the desired hissing sound.

It is thought that the invention and many of its attendant advantages will be understood from the foregoing description and it will be apparent that various changes may be made in the form, construction, and arrangement of the parts without departing from the spirit and scope of the invention or sacrificing all of its material advantages, the form hereinbefore described being merely a preferred embodiment thereof.

We claim:

1. An easily opened reclosure can, comprising in combination:

a tubular sheet metal body having its edges seamed together in a longitudinal side seam, a circumferential slit formed in said body adjacent one end and extending around a major portion thereof, said slit terminating closely adjacent both sides of said side seam,

a peelable tape of metallic foil covering and sealing said slit and being bonded to the adjacent portions of said can body by a thermoplastic resin adhesive of low peel resistance, and

a collar disposed within said can body adjacent said slit for supporting said can body in the area thereof on both sides of said slit, said collar extending longitudinally beyond one portion of said can body after it has been opened along said slit and being engageable with another portion of said can body beyond said slit to provide a reclosure seat therefor.

2. The can of claim 1 wherein a score line is formed in said can body and extends from one end of said slit to the other end thereof, said score line extending completely through all of the layers of said can body in said side seam thereof to provide for complete separation of the portions of said can body on opposite sides of said slit.

3. The can of claim 1 wherein said tape is provided with an unbonded end portion which is folded back on itself to form a pull tab of double thickness.

4. The can of claim 1 wherein a venting perforation is formed in said can body in the portion thereof beneath said tape.
